United States Patent Office

Des. 179,647
Patented Feb. 5, 1957

179,647

SPACE HEATER

John B. Koch, Detroit, Mich., assignor to American Blower Corporation, Detroit, Mich., a corporation of Michigan

Application August 26, 1954, Serial No. 32,033

Term of patent 14 years

(Cl. D81—10)

Fig. 1 is a front elevational view of a space heater embodying my new design; and

Fig. 2 is a side elevational view of the space heater shown in Fig. 1.

The essential features of my design reside in the portions shown in full lines.

I claim:

The ornamental design for a space heater, as shown and described.
